(57) **CLAIM**

The ornamental design for a dome, as shown and described.

DESCRIPTION

FIG. 1 is a perspective view of the dome mounted on a utility meter;

FIG. 2 is a perspective view of the dome;

FIG. 3 is a top view of the dome;

FIG. 4 is a bottom view of the dome;

FIG. 5 is a front view of the dome;

FIG. 6 is a rear view of the dome;

FIG. 7 is a right side view of the dome; and,

FIG. 8 is a left side view of the dome.

The broken line showing of structure is for illustrative purposes only, and forms no part of the claimed design.
